DESIGN FOR A TAILSTOCK

Jesse Srofe, Cincinnati, Ohio, assignor to The
R. K. Le Blond Machine Tool Company, Cin-
cinnati, Ohio, a corporation of Delaware

Application March 16, 1943, Serial No. 109,769

Term of patent 14 years

To all whom it may concern:

Be it known that I, Jesse Srofe, a citizen of the United States and a resident of Cincinnati, county of Hamilton, and State of Ohio, have invented a new, original, and ornamental Design for a Tailstock, of which the following is a specification, reference being had to the accompanying drawings, forming a part thereof.

Figure I is a front view of a tailstock embodying my new design.

Figure II is a rear view of the tailstock shown in Figure I.

Figure III is a plan view of the tailstock shown in Figure I.

Figure IV is a left hand end view of the tailstock shown in Figure I.

Figure V is a right hand end view of the tailstock shown in Figure I.

I claim:

The ornamental design for a tailstock, substantially as shown.

JESSE SROFE.
